UNITED STATES PATENT OFFICE.

PHILIP BELLOWS, OF BOSTON, MASSACHUSETTS, ASSIGNOR TO DAMPNEY COMPANY OF AMERICA, OF BOSTON, MASSACHUSETTS, A CORPORATION OF MASSACHUSETTS.

TUBE-PAINTING MACHINE.

Application filed February 3, 1921. Serial No. 442,098.

To all whom it may concern:

Be it known that I, PHILIP BELLOWS, a subject of the King of Great Britain and Ireland and the Isle of Man, having declared my intention of becoming a citizen of the United States, residing in Boston, Massachusetts, have invented Tube-Painting Machines, of which the following is a specification.

10 In order to preserve the tubes of boilers of a certain type as well as to prevent in a greater or less degree the accumulation of scale, soot or injurious substances upon their inner surfaces it is advisable to apply to 15 such surfaces a coating of protective paint, and one object of this invention is to provide a practical, convenient and efficient machine for applying to and distributing paint on the interior surfaces of tubular structures, more 20 especially to the inner surfaces of boiler tubes; the invention further contemplating means whereby the drying of the painted surfaces may be hastened.

A further object of my invention is to provide 25 a painting machine of the above noted class with novel means whereby it may be suitably supported in position to operate on a series of substantially parallel tubes, the arrangement and construction of the parts 30 being such as to facilitate the quick and convenient mounting of the mechanism on and its removal from such tubes regardless of their number, arrangement and dimensions.

I also desire to provide novel mechanism 35 for insuring the rapid and thorough application of a coating of paint to and its distribution upon the inner surface of a tubular structure, and the invention includes novel means for not only delivering paint at a definite rate in predetermined amounts, but also for repeatedly brushing such paint over 40 the surface to which it is to be applied in a manner simulating that characterizing hand painting.

45 Another object of my invention is to provide a simple and compact mechanism for forcibly delivering paint from a source of supply of the same to the interior surface of a cylindrical structure so that it may be subsequently spread by suitably actuated brushes.

It is also desired to provide a tube painting machine having paint apply-

ing and distributing elements advanced by a suitable step reciprocation through the 55 structure to be painted, together with a device for utilizing such movement of the parts for the operation of paint delivering and distributing devices.

I further desire to provide a relatively 60 simple, compact and reliable mechanism for reciprocating a paint applying and distributing device within a tubular structure and at the same time advancing it through said 65 structure at a rate suitable for the proper application of the paint, the arrangement of parts being such as to automatically maintain a suitable tension on the member or element for moving the paint applying apparatus.

70 These objects and other advantageous ends I attain as hereinafter set forth, reference being had to the accompanying drawings, in which:

Figure 1, is a front elevation of a tubular 75 boiler showing my invention as applied thereto;

Fig. 2, is a side elevation of the apparatus shown in Fig. 1, the boiler and a portion of 80 said apparatus being shown in vertical section;

Fig. 3, is a vertical section on the line 3—3, Fig. 1, and on a larger scale than Fig. 2, illustrating the actuating mechanism for 85 the propelling chain;

Fig. 4, is an elevation of the rear end of the boiler shown in Fig. 5, showing certain portions of my invention as applied thereto;

Fig. 5, is a vertical section on the line 5—5, Fig. 4;

Fig. 6, is a plan, partly in section, of the mechanism constituting my invention, showing in horizontal section the boiler to which 90 said invention is applied;

Fig. 7, is a side elevation, partly in section, of the paint applying and distributing mechanism, showing it in an operative position in a boiler tube;

Fig. 8, is a plan of the mechanism shown in Fig. 7, the boiler tube as before being 100 shown in section;

Fig. 9, is a vertical section on the line 9—9, Fig. 8;

Fig. 10, is a fragmentary horizontal section on the line 10—10, Fig. 9;

Fig. 11, is an inverted elevation of a por-

tion of the mechanism shown in Fig. 7, illustrating the side thereof opposite that illustrated in said Fig;

5 Figs. 12, 13 and 14, are vertical sections on the lines 12—12, 13—13, and 14—14, Fig. 10;

Fig. 15, is a vertical section on the line 15—15, Fig. 7;

Fig. 16, is a side elevation of the structure constituting the paint reservoir;

10 Figs. 17 and 18, are vertical sections on the lines 17—17 and 18—18, Fig. 16;

15 Figs. 19 and 20, are fragmentary elevations respectively illustrating the opposite ends of the paint applying and distributing apparatus;

Fig. 21, is a vertical section on a larger scale than the preceding figures taken on the line 21—21, Fig. 9;

20 Fig. 22, is a side elevation partly in vertical section, illustrating the check valve for the paint reservoir and certain of the parts associated therewith;

25 Fig. 23, is a longitudinal vertical section illustrating the detail construction of one of the paint distributing brushes;

Fig. 24, is a vertical section on the line 24—24, Fig. 23;

30 Fig. 25, is a longitudinal vertical section of the device for supplying paint to the reservoir of my apparatus;

35 Figs. 26 and 27, are respectively a plan and a vertical section on the line 27—27, Fig. 26, illustrating the preferred form of yielding coupling for one of the propelling chains, and

40 Figs. 28 and 29, are respectively a side elevation and a plan of a special feature of my invention.

45 In Figs. 1 to 6 of the above drawings, 1 represents the cylindrical body or shell of a tubular boiler having a front head 2, a rear head 3, and a series of tubes 4 having their ends respectively mounted in said heads. In accordance with my invention, I provide two supporting frames, preferably, though not necessarily, carried by the front and rear heads respectively, and of these frames the first consists in the present instance of a casting having a bottom horizontal member 5, a vertical member 6 and a top horizontal member 7. Each of the members 5 and 7 is connected at one end to and extends at right angles from the member 6, the opposite end being more or less frusto-conical in form and of such dimensions as to fit into the open end of one of the tubes 4 of the boiler.

50 A collapsible gripping device is provided for removably holding these end portions 8 in place against the ends of the tubes, and in Fig. 3 I have illustrated a preferred form of this device which consists of a pair of blocks 9 connected to the heads 8 by rods 10. These blocks have their adjacent faces oppositely inclined for coaction with a slidable wedge

65 member 11 mounted on a threaded rod 12 passing through the head 8 and having its outer end 13 headed to be turned by hand or by a wrench for the purpose of drawing said wedge forcibly between the blocks 9 so as to spread and retain them in gripping engagement with the inner surfaces of the boiler tubes.

70 Extending laterally from the member 5 is a platform or shelf 5^a, which constitutes a support for a motor 46 and a blower 100, and also for a bracket 5^b, the purposes of which are to be set forth hereinafter. The shelf 5^a is preferably provided at its outer edge with a rearward arm 5^c adapted similarly to the member 5 to fit the end of one of the boiler tubes and thereby to constitute an additional support for the said shelf.

75 The front framework of my device also includes a suitable number of frame members 14 similar to the member 5—6—7, with the exception that the extension 5^a is eliminated, the arms 14^a and 14^b being provided with heads 8^a carrying tube gripping devices similar to that shown in Fig. 3 whereby they may be rigidly connected to the boiler structure. In the present instance the member 14 and the frame member 5—6—7 are constructed to removably receive and be rigidly connected by a pair of parallel bars 15 and 16 in the form of tubular members which engage said frame member at the outer ends of its top and bottom portions.

80 If desired, I may also provide supporting or bracing elements 17 each in the form of an arm engaging the lower bar 16 and extending therefrom downwardly and inwardly so as to be capable of entering and being supported by the end of one of the lower boiler tubes, though in some cases it may merely rest against the outer face of the adjacent boiler head, so as to assist in supporting the weight of the remainder of the frame. The tubular supporting bars 15 and 16 may be rigidly connected to the frame members by any suitable means such as set screws 18 (Fig. 3).

85 The frame members 5—6—7 and 14 provide bearings, preferably in their vertical portions, for a substantially horizontal shaft 19 on which are rotatably carried one or any desired number of chain or sprocket wheels 20 whose pitch diameter is substantially equal to the distance between the center lines of a pair of adjacent boiler tubes in the same vertical plane.

90 At the back end of the boiler I provide a second frame structure which in general is similar to that at the front end and consists of a suitable number of supporting brackets 21, each having a bottom member 22, an upright member 23 and a top member 24. These two brackets 21 are connected by lower and upper horizontal bars 25 and

26, in the present instance made of tubular sections, and as before I preferably provide an inclined bracing member or members 27 fixed to the bottom member 25 in position 5 to extend inwardly at an angle so as to transmit a certain part of the downward thrust on the frame to the boiler head. This member may project into and rest upon the projecting end of one of the lower boiler 10 tubes.

In this case the bottom member 22 of the frame is fixed to the bottom horizontal bar 25 independently of the upright bar 23 and carries at its inner end a guide block 28 connected through a bolt 29 to a disc 30 within the boiler tube so as to center and properly support it. The upright members 23 of the brackets 21 provide bearings for a horizontally extending shaft 31 on which are 20 rotatably mounted sprocket wheels 32 of the same construction and dimensions as the sprocket 20 at the front of the boiler, and both sets of sprocket wheels are laterally positioned on their supporting shafts 19 and 25 31 by sleeves or collars 33 thereon.

In order to maintain a suitable tension on the sprocket chains 34 which extend around the coacting sprocket wheels 20 and 32 of each bar, the upright member 23 of 30 each of the rear brackets is free to swing on its supporting bar 25 and each of the bracket members 24 is connected to the top horizontal bar 26 so as to be free to turn thereon. Each of these members 24 has slidably 35 mounted in it a bolt 29^a for holding and positioning its guide block 28 and its centering disc 30 in the boiler tube. A spring 35 is mounted on said bolt between the block 28 and said member 24 as indicated in Fig. 5.

If desired or found necessary to further increase the tension on the chains 34, a second bracket member 24^a may be rotatably mounted on the shaft 31 and formed for 40 sliding engagement with a bolt 29^b, which, as in the case of the bracket member 24, carries a coil spring 35 and is supported by a guide block 28 and a centering disc 30.

As a result of the above construction and arrangement of parts I am enabled to support a number of endless chains 34 each with 50 its two main portions or substantially horizontal runs extending parallel and substantially centrally through a pair of the boiler tubes and maintain these chains at a predetermined constant tension, dependent on the number, design and arrangement of the springs 35.

Within the tubes 4 through which the chains extend I connect to each chain 34, 60 preferably between its ends, a paint supplying and distributing apparatus hereafter described, and for moving said chains with said apparatus longitudinally through the tubes in the manner which I have found to 65 most thoroughly and efficiently apply the

paint, I provide the actuating mechanism shown in detail in Figs 1, 3 and 6.

The mechanism in the present instance consists of a pair of ratchet wheels 36 and 37 having their teeth inclined in opposite 70 directions and both fixed to the front or driving shaft 19. The diameters of said ratchet wheels are different in the present instance, one being substantially twice the diameter of the other and having substantially twice the number of teeth. The ratchet wheel 36 has a pawl 38 cooperating with its teeth and carried on an arm 39 pivotally mounted on a second arm 40 fixed to and projecting from the bottom supporting bar 16. Similarly the ratchet wheel 37 has a coacting pawl 41 carried on an arm 42 pivoted to a second arm 43, likewise fixed to the bar 16. Mounted in suitable bearings in the bracket 5^b is a shaft 45^b having 85 at one end a gear wheel 45, said gear wheel having a crank pin 44 with which the pawl arm 42 is connected by means of an arm 42^a and a bell crank lever 42^b, which latter is pivotally secured to the said arm 42. At the 90 end of the shaft 45^a opposite the gear wheel 45 is a crank arm 45^b, to which is pivotally attached a connecting rod 39^a, the other end of which is pivotally secured to a bell crank lever 39^b pivotally secured to the arm 39. 95

The bell crank levers 42^b and 39^b are respectively connected by means of arms 42^c and 39^c to the pawls 41 and 38, and the movements of the said arms 42^c and 39^c relative to the arms 42 and 39 respectively being 100 limited by pins 42^d and 39^d which extend from the respective arms through slots in the rods 42^c and 39^c, while springs 41^a and 38^a are provided which normally retain the said pawls 41 and 38 in the downward 105 ratchet-engaging position. Continuous rotation of the said shaft 45^a is effected by means of the motor 46 which, through a suitable train of gears, is operatively connected with the said shaft. 110

The various parts are so arranged that when the motor is in operation, the rotation of the gear wheel 45 causes the pawls 38 and 41 to alternately engage and move their coacting ratchet wheels, with the result that the shaft 19 is turned in a counter-clockwise direction through a definite angle by the movement imparted to the ratchet wheel 37 and is immediately thereafter turned through the ratchet wheel 36 in a clockwise direction but through a smaller angle, in the present case half that through which it was turned by the ratchet wheel 37. The sprocket wheels 20 fixed to the shaft 19, and consequently the chains 34, are therefore continuously reciprocated, but since their movement in one direction is double that in the other direction, a given point on each chain and hence the apparatus connected thereto, is advanced from one end of the 115 120 125 130

boiler tube to the other by a succession of reciprocating movements longer in one direction than in the other.

Each of the chains 34 is preferably provided with a spring link 46 so that it is free to yield under abnormal tension conditions and each chain also preferably carries a cam block 47, (Figs. 5, 28 and 29) for the purpose of engaging a switch element 46^a which 10 is operatively associated with the motor 46 whereby when the distributing element has reached the forward end of the tube through which it is being drawn, the switch is automatically thrown open by engagement 15 therewith of the said block 47 and the operation of the motor discontinued.

The apparatus so far described will be seen to consist of a pair of frame structures so made as to be conveniently secured to or 20 removed from the front and rear heads respectively of a tubular boiler and to include pairs of sprocket wheels so positioned and proportioned as to each support an endless chain so that its runs may extend substantially axially through two parallel tubes to be painted. Each of these chains under operating conditions is maintained under a definite required tension and it is driven by a series of power impulses causing it to 30 move alternately in opposite directions, but for different distances so that in addition to being reciprocated it is caused to advance through the tubes.

For supplying paint to the tubes and distributing it on their inner surfaces, I provide the apparatus whose detail construction is illustrated in Figs. 7 to 24 inclusive. This includes a paint container or reservoir 50 of a generally cylindrical outline whose 40 diameter is such as to permit it to freely enter any of the tubes to be painted. One end of this container is formed by a head 51 from which a bearing stud 52 projects axially of said container and terminates in a hook 53 for convenient connection to one end 45 of a chain 34. The opposite end of the paint reservoir is formed with an elongated tubular extension 54 connected to its interior by an intake tube 55 which projects downwardly to within a short distance of its 50 lowest point. The opposite end of the extension 54 has mounted on it a pump casing 56 having a bearing extension in line with the extension 54 and the bearing stud 52. 55 This extension 57 is tubular and has fixed in its extremity a head terminating in a second hook 58 for engagement with the second end of one of the propelling chains 34.

The head 51 of the paint reservoir is provided with an inlet opening controlled by an inwardly opening check valve 59 mounted in a bushing 60 formed to cooperate with the nozzle 61 of a filling gun 62, (Fig. 25). Said reservoir has also at its uppermost portion a normally closed air escape valve 63,

(Fig. 21) whereby as the reservoir is filled the air trapped therein may escape. The extension 54 of the paint reservoir is externally formed to provide a support for a reciprocating cylindrical brush 64, and a second and similar cylindrical reciprocating brush 66 is slidably mounted on the bearing stud 52, the arrangement being such that said brushes are shorter than the structures on which they slide and tend to remain in given positions longitudinally of a boiler tube, which are alternately moved in opposite directions by reason of their engagement with the structures adjacent their ends and the range of movement of the brush 66 is 75 greater than that of the brush 64. These brushes while they may be of any suitable construction for applying and properly distributing paint to the inner cylindrical surface of the tube in which they operate, are 80 each preferably made of two semi-annular bristle-supporting body sections 68, (Figs. 23 and 24) normally pressed apart by springs 69 so that all of their bristles are constantly 85 maintained in engagement with the inner 90 tube surface. These body sections are mounted between the flanges of a sleeve 68^a and are retained in position while allowed a limited radial movement by screws 68^b projecting from the flanges into slots in their 95 ends. The brushes are held from rotating on their structures 52 and 54 by rods 65 projecting from the paint reservoir structure 50 and slidable through slots in the flanges of the sleeves 68^a, (Figs. 15 and 16).

The passage within the tubular extension 54 for the paint reservoir, while communicating with the latter at one end, at its opposite end is connected through a passage 70, (Fig. 9) with the upper portion of a cylindrical cavity 71 in the pump casing 56. This cavity has operative in it a plunger 72 acted on by a spring 73 so that it tends to remain in and return to its outer position in said cavity, from which a passage 74 leads into the bearing extension 57, past a check valve 75 and through one or more outlets 76 into a chamber 77 within the paint distributor 78. This is rotatably mounted on said extension 57 and in the present case 105 consists of a flat cylindrical structure having radially extending passages 79 whose inner ends open into its cavity 77, so that liquid entering the latter may flow outwardly 110 through these passages.

In order that the streams of paint delivered from this member 78 may be best distributed upon the inside surface of the tube being painted, I provide means whereby said member is rotated on its supporting bearing structure 57. For this purpose I mount on it a sprocket wheel 80 concentric with the bearing structure 57 and provide means whereby it is rotated by the reciprocation of the paint delivering and distributing unit 125 130

as a whole. This means consists in the present instance of an arm 81 pivotally mounted on a screw 82, (Fig. 10) carrying a spring supported finger 83 positioned to engage the 5 teeth of the sprocket wheel 80 and to impart to said sprocket wheel a rotary motion while the mechanism is operating. The arm 81 under the action of a spring 84 tends to remain in one of its extreme positions in engagement with a stop 85, (Fig. 7), and for the purpose of periodically swinging it on its pivot away from said stop to its other extreme position I mount on it a roller 86 in position to be engaged by the head 90 10 of a rod 87 slidably guided in a suitable bearing lug on the paint reservoir structure 50.

The headed end of this rod extends through the brush structure 64 and is supported by that flange thereof nearest the pump, having 20 on it a spring 89 confined between said flange and a collar 88 in such manner as to tend to keep the head 90 against the flange. The opposite end of the rod 87 projects beyond the reservoir structure 50 in position 25 to be acted on by the second paint brush 66, as said reservoir with its associated parts moves in one direction relatively to said brush.

If it is desired to apply a coating of paint 30 to the tubes of a boiler the front and rear frame structures are suitably mounted on the front and rear heads of the boiler, as shown in Figures 1 to 6 inclusive, by properly inserting and expanding the various 35 sets of gripping devices as previously explained. The parts are so positioned that each of the sprocket wheels 32 carried by the front frame are in the same vertical plane as a similar sprocket wheel carried by the 40 rear frame and will support a chain 34 so that its two parallel runs extend substantially in the line of the axis of two boiler tubes.

The paint reservoir 50 of a paint applying 45 and distributing unit is then filled with paint preferably from a filling gun such as that illustrated in Fig. 25, and such unit is then introduced into one of said boiler tubes with its hooked ends 53 and 58 connected 50 to the ends of one of the chains 34. Under the action of the tension springs 35 the arms 23 and with them the sprockets 32 which they carry are swung outwardly away from the rear head 3 of the boiler, maintaining 55 such a tension on the two runs of the chain 34 as will at all times take up any lost motion and maintain said runs substantially axial of the boiler tubes 4 through which they extend.

60 If now the electric motor 46 be put in operation, the shaft 19 through the two sets of ratchet mechanism is alternately rotated in opposite directions but through unequal angles so that the upper run of the chain 65 and hence of the paint distributing unit at-

tached thereto is first moved a distance of, for example, three inches into the boiler tube in which it is inserted and is then moved two inches more or less in the opposite direction. As a consequence said unit is gradually advanced through the boiler tube from one end to the other. 70

Referring to Figures 7 to 9, it will be noted that if the painting unit be first moved toward the left for example, the paint 75 brushes 64 and 66 owing to the frictional engagement of their bristles with the boiler tube, lag behind until the first of them is engaged by the adjacent end of the paint reservoir 50 and the second brush is engaged by 80 the flange of the hook 53, after which both brushes move with the unit toward the left.

If now the direction of movement of the painting unit be reversed, the two brushes again remain stationary until the brush 64 85 comes into engagement with the head 91, whereupon this latter is moved longitudinally in its guideway in the pump structure 56 against the action of the spring 91^a and through the arms 92 and 93 forces the 90 pump plunger 72 into its cylinder. Following this, the spring supported pawl 83 is moved into the plane of the sprocket wheel 80 of the paint distributing member 78, the second brush 66 striking the adjacent end 95 of the rod 87 and moving this against the action of the spring 89 so that its head 90, acting on the roller 86, turns on its pivot 82 the arm which carries the pawl 83. The latter is thereupon brought into engagement 100 with the teeth of the sprocket wheel 80 and causes this to make a partial revolution in one direction, thus rotating the distributing member 78, and causing the contained material to be thrown out against the tube walls. 105

After the direction of movement of the paint unit has been again reversed, the disengagement of the head 90 from the brush 64 permits the spring 71 to raise the pump plunger 72 or move it outwardly in its cylinder so that it draws a charge of paint into the latter from the reservoir 50 through the inlet pipe 55 and tubular structure 54. Likewise the relative movement of the brush 64 and pump structure 56 allows the spring 115 84 to swing the arm 81 on its pivot, thereby returning the spring supported pawl 83 to its upper or normal position at the same time the relative movement of the various parts permits the spring 89 to move the rod 120 87 to the position shown in Fig. 7, with its head 90 in engagement with the adjacent flange of the brush 64.

Obviously the repeated movement of the 125 paint unit in opposite directions and the resulting reciprocation of the pump plunger 72 causes paint to be drawn from the reservoir 50 through the pipe 55 and tubular structure 54 into the cylinder from which it is forced through the passage 74 into the 130

distributing member 78. The above described relative movement of the brushes and consequent turning of the member 78 causes the streams of paint discharged into the passages 79 to be delivered upon the inner surface of the boiler tube in helical lines, it being obvious that the number of these discharge openings 79 may be varied so that paint may be distributed for at least the full circumference of the circular tube section.

As will be understood from the above description, the paint unit shown in Figs. 7 to 9 for example, is designed to advance toward the left so that after the paint has been applied by the member 78 in a series of more or less helical lines to the inner surface of the boiler tube, it is engaged first by the brush 64, which moving back and forth spreads it in a film more or less completely over the inner surface of said tube. This partially spread paint is thereafter engaged by the brush 66 and is still further spread or distributed so that it takes the form of a well brushed, evenly distributed coat. When the paint applying and distributing unit has moved from one end of the tube to the other and has coated its interior surface as above described, the motor is stopped and without disconnecting from the upper run of the chain 34, it is preferably drawn back through the tube by the rear chain, the front chain hook having been disconnected. In this way, any mark left on bottom of tube by the chain in passing through is eliminated. The mechanism always works in one direction only. It is always started from the same end of the tube.

Obviously while I may employ but a single painting unit, if desired any suitable number of units may be actuated from the shaft 19 at the same time, and after the application of paint to all of the tubes of one set, the position of the front and rear supporting frames may be altered so that the two runs of the chain or chains 34 may be extended through two other tubes. The paint unit may then be put in operation as above described to coat another tube.

If it be desired to hasten the drying of the paint or coating applied to the tubes, I may connect to the electric motor 46 a suitable fan or blower 100, and from this run an air delivery pipe 101 having outlets arranged to discharge into one or more tubes after they have been painted, it being understood that the conduit or pipe 101 is preferably flexible so as to be easily adapted to deliver air to any or a number of the boiler tubes after these have been painted.

I claim:

1. In a tube coating machine, apparatus adapted to pass through a tube and comprising mechanism operative by its movement in

the tube for distributing a coating material over the surface thereof; and mechanical means for reciprocating said apparatus within the tube.

2. In a tube coating machine, apparatus adapted to be passed through a tube and comprising mechanism operative by movement of the apparatus in the tube for depositing a coating material upon the tube surface; means for spreading the material over said surface; and mechanism for reciprocating the apparatus within the tube by a succession of opposite movements, of which those in one direction are greater than those in the opposite direction.

3. In a tube coating machine, apparatus adapted to be passed through a tube and comprising, in combination, depositing mechanism, and an element capable of movement relative to said mechanism and adapted to frictionally engage the walls of the tube thereby to be rendered relatively immovable, said element being operatively connected with said mechanism whereby the latter is actuated when the structure is moved in the tube.

4. In a tube coating machine, apparatus adapted to be passed through a tube and comprising, in combination, a container, depositing mechanism, means for delivering coating material from the said container to the depositing mechanism, and means for actuating said depositing mechanism.

5. In a tube coating machine, apparatus adapted to be passed through a tube and comprising, in combination, a container, depositing mechanism, a duct extending from the container to the depositing mechanism, and a pump for forcing coating material through said duct from the container to the depositing mechanism.

6. In a tube coating machine, apparatus adapted to be passed through a tube and comprising, in combination, a container, mechanism for pumping a coating material from the container and depositing it on the surface of the tube, a brush adapted to distribute the said coating material over the surface; and means for reciprocating the apparatus in the tube.

7. In a tube coating machine, apparatus adapted to be passed through a tube and comprising, in combination, a container, a rotary depositing element, means for delivering coating material from the container to the depositing element, and mechanism for rotating said element.

8. In a tube coating machine, apparatus adapted to be passed through a tube and comprising, in combination, a container, a depositing element, a duct connecting said container and element, a brush capable of limited movement relative to said element and adapted to frictionally engage the walls of the tube, said friction tending to retain

said brush immovable, and mechanism actuatable by contact with said brush for operating said depositing element.

9. In a tube coating machine, apparatus adapted to be passed through a tube and comprising, in combination, a container, a brush capable of limited movement with respect to said container and adapted to frictionally engage the walls of said tube, said friction tending to retain said brush immovable when the apparatus is moved in the tube, and mechanism actuated by engagement with said brush for withdrawing a coating material from the container and depositing it upon the walls of said tube.

10. In a tube coating machine, apparatus adapted to be passed through a tube and comprising, in combination, a container for a coating material, a pair of brushes capable of limited movement relative to said container and adapted to frictionally engage the walls of said tube, said engagement tending to retain said brushes immovable when the apparatus is moved in the tube, a rotary depositing element, a duct connecting said container and element, pump mechanism adapted to deliver the coating material from the container to the depositing element, mechanism for rotating said depositing element, and means whereby said pump and element-rotating mechanisms are respectively actuated by contact with said brushes.

11. In a tube coating machine, apparatus adapted to be passed through a tube and comprising, in combination, a container, a brush, mechanism whereby a coating material is withdrawn from said container and deposited upon the walls of said tube in advance of said brush; and mechanism for bodily moving the container and brush longitudinally through the tube.

12. In a tube coating machine, apparatus adapted to be passed through a tube and comprising, in combination, a container for coating material, means for reciprocating said container in the tube, and mechanism whereby at each reciprocation of the container in the tube the coating material is drawn therefrom and deposited upon the walls of said tube.

13. In a tube coating machine, apparatus adapted to be passed through a tube, and mechanism for passing said apparatus through the tube in a series of reciprocations in which the forward travel is greater than the rearward, said apparatus comprising a container for coating material, mechanism operable at each rearward travel of the apparatus whereby a portion of said coating material is drawn from said container and deposited upon the walls of the tube, and means operable upon each forward travel of the apparatus for spreading the said deposited material over the said surface.

14. In a tube coating machine, apparatus adapted to be passed through a tube, mechanism for advancing said apparatus through a tube in a series of reciprocations in which the forward movement is greater than the rearward, said apparatus comprising a container, a brush capable of limited movement with respect to said container and adapted to frictionally engage the walls of the tube, said engagement tending to retain the brush immovable when the apparatus is moved in the tube, and depositing mechanism mounted in advance of said brush and adapted to be actuated by contact with said brush at each rearward movement of the apparatus in the tube.

15. In a tube coating machine, apparatus adapted to be passed through a tube and comprising, in combination, a container, a brush capable of limited movement relative to said container and adapted to frictionally engage the walls of the tube, said frictional engagement tending to retain the brush immovable when the apparatus is moved in the tube, a rotary depositing element, means for discharging a coating material from the container into the depositing element, a ratchet wheel connected with said element, a pivotally mounted pawl, and an operating rod for said pawl adapted to be actuated by contact with said brush when the apparatus is moved in the tube.

16. In a tube coating machine, apparatus adapted to be passed through a tube and comprising, in combination, a container, a depositing element, a duct connecting said container and element, a reciprocatory pump element adapted to force a coating material from the container to the depositing element, an oscillatory element adapted to reciprocate said pump element, a brush capable of limited movement relative to said pump mechanism, and a member adapted to be shifted by contact with said brush for oscillating said oscillatory element.

17. In a tube coating machine, the combination with apparatus adapted to be passed through a tube, of mechanism for reciprocating said apparatus in the tube, and mechanism associated with said apparatus whereby said reciprocation effects the deposit upon the surface of the tube of a coating material and the spreading of said material over the said surface.

18. In a tube coating machine, apparatus adapted to be passed through a tube and comprising mechanism for distributing a coating material over the surface of said tube, and mechanism for advancing the said apparatus through the tube in a series of reciprocatory steps, the forward movement of each reciprocation being greater than the rearward movement.

19. In a tube coating machine the com-

- bination with an apparatus adapted to be passed through a tube for distributing a coating material on the surface of said tube, of mechanism for advancing said apparatus through the tube in a series of reciprocations, the forward movement of each reciprocation being greater than the rearward movement thereof, said advancing mechanism comprising a shaft at each end of said tube, a sprocket on each of said shafts, a sprocket chain mounted on said sprockets and having the ends thereof attached to opposite ends of said distributing apparatus, a pair of ratchet wheels adapted by means of oscillating pawls to rotate the said shafts alternately in different directions, one of said ratchets being of greater diameter than the other whereby the said oscillations of the shafts are greater in one direction than in the other, and mechanism for oscillating said pawls.
20. In a tube coating machine, the combination with a pair of frames adapted to be supported in the opposite ends of the tubes 25 of a boiler, each of said frames supporting a shaft having thereon a sprocket, of apparatus adapted to be drawn through said tubes for distributing a coating material on the interior surfaces thereof, a chain upon 30 said sprockets, the ends of which chain are attached to the opposite ends of said distributing apparatus, and mechanism carried by one of said frames for rotating the sprockets to cause the drawing of said distributing apparatus through one of the tubes, one of said frames comprising means 35 for retaining the said chain under a constant tension.
21. In a tube coating machine, the combination with apparatus adapted to be passed 40 through a tube for distributing a coating material on the interior thereof, of mechanism including a sprocket at each end of said tube and a chain mounted on said 45 sprocket and having its ends attached to opposite ends of said apparatus, a driving element for said sprockets, and means attached to said chain for discontinuing the operation of said driving element when the said distributing apparatus has reached the forward 50 end of the tube.
22. In a tube coating machine, the combination with apparatus adapted to be passed 55 through a tube for distributing a coating material over the inner surface thereof, of mechanism for drawing said apparatus through the tube, and means associated with said mechanism for directing a draft of air through the said coated tubes.
60. 23. In a tube coating machine, apparatus adapted to be passed through a tube and comprising, in combination, a container, a rotary depositing element, means for delivering coating material from the container to the depositing element, and mechanism 65 for rotating said element for effecting the depositing of the contained material upon the walls of the tube.
24. In a tube coating machine, apparatus adapted to be passed through a tube and 70 comprising, in combination, a container, a rotary depositing element consisting of a hollow casing having substantially radial apertures in the periphery thereof, means for delivering coating material from the 75 container to the depositing element, and mechanism for rotating said element.
25. The combination in a tube coating machine of a brush; mechanism for automatically applying a coating material to said 80 brush; and mechanism for reciprocating the brush and at the same time progressing it through the tube.
26. The combination in a tube coating machine of a brush formed to frictionally engage the inside surface of a tube; a reservoir for coating material mounted to move relatively to the brush; a pump having its cylinder and plunger respectively connected to the brush and to the reservoir; with 85 means for reciprocating the brush in a tube to cause the pump to deliver the coating liquid from the reservoir to the tube.
27. The combination in a tube coating machine of a brush formed to frictionally engage the inside surface of a tube; a reservoir for coating material mounted to move relatively to the brush; a pump having its cylinder and plunger respectively connected to the brush and to the reservoir; means for reciprocating the brush in a tube to cause 90 the pump to deliver the coating liquid from the reservoir to the tube; with means for longitudinally progressing the brush and reservoir as a unit through the tube.
28. The combination in a tube coating machine of a brush formed to frictionally engage the inside surface of a tube; a reservoir for coating material mounted to move relatively to the brush; a pump having its cylinder and plunger respectively connected to the brush and to the reservoir; means for reciprocating the brush in the tube to cause 95 the pump to deliver the coating liquid from the reservoir to the tube; with means for rotating the brush as it is moved in the tube.
29. The combination in a tube coating machine of at least one brush formed to operate on the inside surface of a tube; a reservoir; a pump; a device for depositing on the inside surface of a tube the coating material drawn from the reservoir by the pump; means for causing the pump to be actuated by relative movement of the brush and one of the pump members; with mechanism for reciprocating the brush with the pump and depositing device in a tube.
30. The combination in a tube coating ma-

chine of at least one brush formed to operate on the inside surface of a tube; a reservoir; a pump; a device for depositing on the inside surface of a tube the coating material drawn from the reservoir by the pump; means for causing the pump to be actuated by relative movement of the brush and one of the pump members; and mechanism for reciprocating the brush with the pump and 10 depositing device in a tube and progressing said apparatus through the tube.

31. In combination, a brush shaped to engage the inside of a tube, means for pulling said brush through said tube, and means for 15 automatically depositing material in advance of said brush in quantities proportional to the progress of said brush through the tube.

32. In combination, a brush shaped to engage the inside of a tube, means for pulling 20 said brush through said tube, and means for automatically depositing material in advance of said brush in quantities proportional to the progress of said brush through the tube, said means being actuated by 25 movement of the device through the tube.

33. In combination, applying means, spreading means, mechanism for moving both said means over a surface to be coated, and feed means actuated by said movement 30 for producing a flow of said applying means, whereby said flow is proportional to the rate of progress of the device over the surface.

PHILIP BELLows.
